CONCRETE DECK AND WALL FORM
CONSTRUCTION

Takeo Sato, Honolulu, Territory of Hawaii

Application June 19, 1951, Serial No. 232,358

7 Claims. (Cl. 25—131.5)

1

This invention relates to adjustable collapsible forms used in concrete construction, and in particular collapsible forms that are readily set up and taken down after use and that are readily adjustable to form walls, floors, and the like in buildings of different dimensions.

The purpose of this invention is to provide means in a form, channel-shaped in cross section whereby mounting members extended from the ends of units of the form are adjustably mounted in the channel-shaped units.

Various types of connections have been provided in the ends of wall and floor forms for use in concrete construction but where the ends of the forms are adjustably connected it is difficult to frame connecting elements into spaces at the ends of the forms and at the same time provide a smooth wall surface all of the way to the connecting wall or joint. With this thought in mind this invention contemplates forming walls and deck or floor forms, channel-shaped in cross section and providing telescoping or slidably mounted tongues in the ends of the sections whereby the tongues are extended to correspond with the length or width of a floor or wall and secured in position by nails extended through openings in the forms and wood strips in the tongues and in which the areas between the ends of the sections and ends of the tongues are filled in with wood strips to provide a continuous wall surface.

The object of this invention is, therefore, to provide collapsible forms for concrete construction in which tongues are adjustably mounted in the ends of units of the forms for extending the length thereof.

Another object of the invention is to provide means for forming wall forms with tongues adjustably mounted in the ends of sections thereof in which the tongues are held by nails to facilitate setting up and taking down the forms.

A further object of the invention is to provide adjustable elements in the ends of units of deck and wall forms in which the forms are of simple and economical construction.

With these and other objects and advantages in view the invention embodies deck and wall forms provided in units with each unit including a facing plate reinforced at the center and also at the edges with structural shapes, with spaced box-like members positioned in the ends and with tongues having wood strips therein adjustably mounted between the said box-like members.

Other features and advantages of the invention will appear from the following description taken in connection with the drawings wherein:

Figure 1 is a view looking upwardly toward the

2

under side of a deck form with intermediate parts of the form broken away and with the adjusting tongues extended at both ends of the units of the form.

5 Figure 2 is a cross section through the form assembly shown in Figure 1 taken on line 2—2 thereof.

Figure 3 is a similar section taken on line 3—3 of Figure 1.

Figure 4 is a detail on an enlarged scale taken on line 4—4 of Figure 1 showing a longitudinal section through one of the tongues that are adjustably mounted in the ends of the sections of the form.

15 Figure 5 is a longitudinal section taken on line 5—5 of Figure 4 also showing a section through one of the tongues and illustrating the mounting of the tongues in the ends of the sections of the form.

20 Figure 6 is a detail taken on line 6—6 of Figure 5 showing one of the box-like members in the ends of the form.

Figure 7 is a section taken on line 7—7 of Figure 4 showing a cross section through one of the forms and illustrating the mounting of the tongues in the form.

Figure 8 is a side elevational view illustrating one of the extensible tongues of the forms.

Figure 9 is an end elevational view of one of the tongues.

30 Figure 10 is a view similar to that shown in Figure 1 illustrating a connection between two sections of the forms and positioned intermediate of the length of a wall, floor, or the like.

35 Figure 11 is a cross section taken on line 11—11 of Figure 10 showing the arrangement of the parts.

Figure 12 is a similar section taken on line 12—12 of Figure 11 showing the pins for connecting the box-like members in the ends of the form.

40 Figure 13 is a view similar to that shown in Figure 1, on an enlarged scale, illustrating a further modification wherein the telescoping tongues are mounted in U-shape channels.

45 Figure 14 is a longitudinal section taken on line 14—14 of Figure 13 showing the construction of the U-shape channels in the ends of the form.

Figure 15 is a cross section through an end of one of the forms, taken on line 15—15 of Figure 13 illustrating the structure at the ends and in one side of the forms and showing the nails extended into wooden strips in the tongues adjustably mounted in the form.

50 Figure 16 is a longitudinal section taken substantially on line 14—14 of Figure 13 illustrating

the construction of one of the telescoping tongues.

Figure 17 is a detail showing a section taken on line 17-17 of Figure 14 looking upwardly and illustrating the method of mounting the U-shape or channel section with the ribs in the ends of the form. 5

Referring now to the drawings wherein like reference characters denote corresponding parts the improved deck and wall form of this invention includes a plurality of units each having a 10 face plate 10 with T-shaped intermediate reinforcing bars 11, L-shaped reinforcing bars 12 and 13 at the edges and box-like members 14 and 15 at one end and on one side of the bar 11, with similar members 16 and 17 on the opposite side of the bar 11 and similar members 18 and 19 on one side of the bar 11 at the opposite end and 20 and 21 on the opposite side of the said bar. 15

The telescoping or extensible tongues are similar and the same reference numerals are used for the tongues throughout the drawing. The box-like members are spaced providing slots 22 and the tongues are positioned in these slots, as illustrated in Figure 2. 20

The tongues are shown in detail in Figures 4, 5, 8 and 9 and, as shown in Figures 8 and 9 the tongues are provided with base sections 23 having extending webs 24 and 25 at the sides and flanges 26 and 27 at the ends of the webs are positioned perpendicularly to the longitudinal center of the tongue. The flanges are provided with bolt holes 28 and 29, respectively and holes for nails and the like as indicated by the numeral 30 are positioned above and below the bolt holes. 25

The side walls or webs 24 and 25 of the tongues are also provided with spaced nail holes 31 and 32, respectively and similar holes are provided in the base 23 as indicated by the numeral 33. Each tongue is provided with a wood strip 34 to facilitate retaining nails therein. 30

With the parts as shown, particularly in Figures 4 and 5 the tongue is positioned between box-like members 16 and 17 and secured in position by nails 35 which are driven through elongated openings 36, in the member 16 and 37 in the member 17 whereby the tongue is rigidly secured in position between the box-like members. 35

As illustrated in Figures 2 and 4 the upper edges of the tongues are spaced from the outer surfaces of the face plate 10 and where the tongues extend beyond the ends of the sections this area is filled with strips 38 that are secured in position by nails 39 which extend into the strips 34. 40

The flanges 26 and 27 on the extended ends of the tongues are secured to side forms, as indicated by the numeral 40, by nails 41. The ends of the sections may also be supported by beams 42, as shown in Figure 4. 45

The box-like members in the ends of the sections of the form are also used for holding ends of sections together intermediate of the length of a wall, floor, or the like and, as illustrated in Figure 10, rods 43 are inserted through openings 44 in the ends of the box-like sections with the form sections positioned end to end. These connections are also illustrated in Figures 11 and 12. 50

The units of the forms may also be provided with openings in the reinforcing bars 12 and 13 for pins 45 as shown in Figure 1 and similar openings may be provided in the face plates 10, as indicated by the numeral 46. 55

In the design illustrated in Figures 13 to 17, inclusive, the forms include face plates 47 which are provided with intermediate T-shaped reinforcing bars 48 and L-shaped bars 49 and 50 at the edges and U-shaped tongues 51 having flanges 52 and 53 on the ends of side walls 54 and 55, respectively, are slidably mounted in channel shaped sections 56 having side walls 57 and 58, which are mounted on the under surfaces of the face plates 47. 60

The U-shape channels in which the tongues are slidably held are secured in position between the bars 48 and the bars 49 and 50 and by ribs 59 and 60 at the outer ends, and 61 and 62, at the inner ends. The ribs and channel-shaped members are secured in position on the under surfaces of the face plates by welding, or other suitable means. 65

The tongues 51 are provided with elongated slots 63 in the lower surfaces through which nails 64 may be driven into wood strips 65 positioned in the tongues, and the side walls 54 and 55 may also be provided with nail holes 66 through which nails, driven through corresponding nail holes 67 in the side walls 57 and 58 of the U-shape members 59 extend. With these openings aligned nails 68, as shown in Figures 13 and 15 may be driven through the tongues. 70

In this design flanges on the ends of the tongues are secured by nails 69 to supporting panels 70. 75

With the units of the forms formed in this manner the deck or fall form is readily set up by adjusting the positions of the tongues in the box-like members in the ends of the forms and with the flanges at the ends of the tongues secured against frame or wall side forms, as indicated by the numerals 40 or 70, the forms may readily be filled with concrete or a concrete floor may be poured thereon. 80

It will be understood that modifications may be made in the design and arrangement of the parts without departing from the spirit of the invention. 85

What is claimed is:

45 1. A collapsible concrete form comprising an elongated section channel-shaped in cross section and having spaced box-like members in the ends, and tongues having flanges on extended ends thereof adjustably mounted between the said box-like members. 90

2. A concrete form comprising an elongated unit having elongated rectangular shaped face plates with L-shaped reinforcing bars extending downwardly from the edges, a T-shaped bar parallel to the L-shaped bars positioned midway between the said L-shaped bars and mounted on the under surface of the face plate, and spaced box-like members on the ends of the said units and positioned between the T-bar and L-shaped bars on the edges of the units. 95

3. A concrete form comprising an elongated unit having elongated rectangular shaped face plates with L-shaped reinforcing bars extended downwardly from the edges, a T-shaped bar parallel to the L-shaped bars positioned midway between the said L-shaped bars and mounted on the under surface of the face plate, spaced box-like members on the ends of the said units and positioned between the T-bar and L-shaped bars on the edges of the units, and elongated tongues U-shaped in cross section and having filling strips therein and flanges on the ends adjustably mounted between the said box-like members. 100

75 4. A concrete form comprising an elongated

unit having elongated rectangular shaped face plates with L-shaped reinforcing bars extended downwardly from the edges, a T-shaped bar parallel to the L-shaped bars positioned midway between the said L-shaped bars and mounted on the under surface of the face plate, spaced box-like members on the ends of the said units and positioned between the T-bar and L-shaped bars on the edges of the units, elongated tongues U-shaped in cross section and having filling strips therein and flanges on the ends adjustably mounted between the said box-like members, and filling strips positioned against the tongues and at the ends of the said units.

5. A concrete form comprising an elongated unit having elongated rectangular shaped face plates with L-shaped reinforcing bars extended downwardly from the edges, a T-shaped bar parallel to the L-shaped bars positioned midway between the said L-shaped bars and mounted on the under surface of the face plate, spaced box-like members on the ends of the said units and positioned between the T-bar and L-shaped bars on the edges of the units, elongated tongues U-shaped in cross section and having filling strips therein and flanges on the ends adjustably mounted between the said box-like members, and filling strips positioned against the tongues and at the ends of the said units, said tongues and units having spaced openings therein for nails, bolts and the like.

6. A collapsible concrete form comprising an elongated section channel-shape in cross section and having channel-shaped members longitudinally positioned on the under surfaces of the webs of the channel-shaped sections and U-shape tongues slidably mounted in the said channel-shape members.

7. A collapsible concrete form comprising an elongated rectangular shape face plate having longitudinally disposed reinforcing bars extended from one of the surfaces thereof and having longitudinally disposed mounting members U-shape in cross section positioned between the said reinforcing bars, and telescoping tongues also U-shape in cross section and having wood strips therein slidably mounted in the said U-shape mounting members.
